Filed Aug. 26, 1968, Ser. No. 13,277

Term of patent 14 years

Int. Cl. D12—14

U.S. Cl. D90—20

FIG. 1

FIG. 2

FIG. 3

FIG. 1 is a perspective view of a tire showing our new design;

FIG. 2 is a fragmentary plan view of the design shown in FIG. 1; and

FIG. 3 is a transverse sectional view through the tire substantially on the plane indicated by the line 3—3 in FIG. 2.

It is to be understood that the tread pattern continues as shown in the foreground in FIG. 1 throughout the circumference of the tire.

We claim:

The ornamental design for a tire, substantially as shown and described.
